(57) **CLAIM**

The ornamental design for a board for ladder ball, darts, and corn hole games, as shown and described.

DESCRIPTION

FIG. 1 is a front perspective view of a board for ladder ball, darts and corn hole games with removable rungs, showing my new design;

FIG. 2 is a front perspective view of FIG. 1 with two lower rungs removed for complete disclosure;

FIG. 3 is a front elevation view of FIG. 1;

FIG. 4 is a right side view of FIG. 3;

FIG. 5 is a left side view thereof;

FIG. 6 is a top plan view thereof;

FIG. 7 is a bottom plan view thereof;

FIG. 8 is a rear elevation view of FIG. 2;

FIG. 9 is a rear perspective view of the board for ladder ball, darts and corn hole games of FIG. 2 positioned for a corn hole game and with the two lower rungs removed for complete disclosure; and,

FIG. 10 is a front perspective, exploded view of the board for ladder ball, darts and corn hole games of FIG. 1.

1 Claim, 8 Drawing Sheets
